UNITED STATES PATENT OFFICE.

ALFRED C. ABRAMSON, OF ROCKFORD, ILLINOIS.

DESIGN FOR A SEWING-MACHINE TABLE.

SPECIFICATION forming part of Design No. 84,185, dated March 5, 1901.

Application filed January 31, 1901. Serial No. 45,523. Term of patent 3½ years.

To all whom it may concern:

Be it known that I, ALFRED C. ABRAMSON, a citizen of the United States, residing at Rockford, in the county of Winnebago and State of Illinois, have invented and produced a new and original Design for Sewing-Machine Tables; and I do hereby declare the following to be a full, clear, and exact description of the same, reference being had to the accompanying drawing, forming a part thereof.

The accompanying drawing is a perspective view of the new design for sewing-machine tables.

The design consists in a sewing-machine table substantially of the configuration shown.

The sewing-machine table comprises the top 1, frame 2, and cover 3. From the top extend frames consisting of the horizontal divisions 4 and vertical supports 5. A drawer

6 is supported by each division 4, and the fronts of the drawers and horizontal divisions are rounded. A front 7 is located beneath the top and extends between the upper set of drawers. An inclined front 8 is located beneath the top and extends from the front face downward toward the rear face.

Having described my invention, what I claim as new, and desire to secure by Letters Patent, is—

The design for a sewing-machine table substantially as herein shown and described.

In testimony whereof I have signed my name to this specification in the presence of two subscribing witnesses.

ALFRED C. ABRAMSON.
